FURNACE.

No. 297,768.

Patented Apr. 29, 1884.

A technical drawing of a vertical rectangular component. The component features a central vertical slot and a small circular hole near the bottom. It is enclosed within a dashed elliptical outline, suggesting it is a part of a larger assembly or a specific functional module.

UNITED STATES PATENT OFFICE.

JEAN PIERRE COTIART, OF HAVANA, CUBA.

FURNACE.

SPECIFICATION forming part of Letters Patent No. 297,768, dated April 29, 1884.

Application filed April 10, 1883. (No model.) Patented in England February 3, 1883, No. 590, and in France February 16, 1883, No. 141,458.

To all whom it may concern:

Be it known that I, JEAN PIERRE COTIART, a citizen of the Republic of France, residing at Havana, in the Island of Cuba and Kingdom of Spain, have invented certain new and useful Improvements in Furnaces, (for which I have obtained Letters Patent of Great Britain, No. 590, bearing date February 3, 1883,) of which the following is a specification.

10 My invention relates to improvements in furnaces for raising steam, or other heating purposes; and the object of my improvements is to construct furnaces in which green sugar-cane refuse, sawdust, and other waste material 15 may be consumed without previous drying, thus turning rubbish to profitable account and utilizing it for raising steam or other heating purposes.

To this end my improvements consist in certain novel devices and combinations, herein-after fully set forth.

In the accompanying drawings, Figure 1 is a longitudinal section; Fig. 2, a sectional plan; Fig. 3, a transverse section; Fig. 4, a front elevation of a furnace embodying my invention, and Fig. 5 a plan of a portion of one of the layers of fire-bars.

The exterior wall, *a*, of the furnace is constructed, preferably, of refractory material—such as fire-brick or silica—and the fire-bridge *b*, which is built higher than usual, has its upper end inclined, projecting upward and toward the fire-doors of the furnace, in order that it may deflect the flame and heat upon the material to be consumed, and thus assist combustion. The fire-bars are arranged in two separate inclined layers, the upper, *c*, being nearest the fire-doors, and the lower, *d*, interposed between the former and the fire-bridge. Each of these layers is supported at the end nearest the fire-doors by rollers *e* and *f*, which extend across the inside of the furnace, and are carried by movable brackets *e'* and *f'*, which are secured to shafts *e*² and *f*², respectively. The shafts *e*² *f*² have each a worm-wheel at one end, which gears into a worm, and thus enables the fireman readily to raise or lower the fire-bars *c* and *d* into any required position; or, instead of employing worms and worm-wheels,

the fire-bars may be raised or lowered by means of balance-weights, or in any other convenient manner, so as to be accomplished smoothly and without undue friction. The upper shaft, *e*², is mounted in bearings in a box-girder frame, *g*, the lower part of which frame forms the lintel for the doors *h* at the front of the furnace. By this arrangement the shaft *e*² may be easily removed when desired. The lower shaft, *f*², is made in two pieces coupled together, to facilitate removal, and is carried by bearings in wall-boxes *j*³. The opposite ends of the fire-bars *c* and *d* clip over stationary bearing-bars *i* and *j*, respectively, on which they rest. A horizontal tumbling-plate, *k*, and a small stationary inclined plate, *k'*, (both perforated with a series of slots,) are placed close to the bridge, below and beyond the lower layer of fire-bars, *d*. The green sugar-cane or other refuse is put into the top of the furnace through doors *l*, which are closed after its entrance by means of counter-weights *l'*, (see Fig. 3,) and falls on the inclined layers of fire-bars *c* and *d*, to be consumed. Suitable feed mechanism should be added above the doors *l*, to enable the material which is to be consumed to be readily supplied in proper quantities.

When it is desired to clean out the furnace and remove the ashes, the tumbling-plate *k* (which is secured to a shaft, *k*², having bearings in wall-boxes *k*³) may be lowered by means of a worm-wheel keyed or secured to the shaft *k*², and actuated by a hand-wheel, *k*⁵, from the outside of the furnace by a worm at the end of a shaft, *k*⁴, and the ashes can then be withdrawn from the furnace through one of the front doors, *h*. Small sections of grid-plates *m* are suspended from the stationary bearing-bar *i*, in order to admit air, and thereby assist combustion, and also to prevent the green sugar-cane or other refuse from working out at the back of the layer of fire-bars *d*.

Steam-blast pipes *n* are placed on either side of the furnace, and are arranged, preferably, in the manner shown in Fig. 4. These steam-blasts increase the draft, and thus insure the rapidity of combustion necessary for burning sawdust, green refuse, and other waste material without previous drying.

I use, by preference, two inclined layers of fire-bars; but I do not confine myself to that or any other number of layers.

I claim as my invention and desire to secure 5 by Letters Patent—

1. In a furnace for raising steam or other heating purposes, the combination, substantially as set forth, of a deflecting fire-bridge, two or more movable inclined layers of fire-bars, a tumbling-plate, and a steam-blast pipe or pipes.
- 10 2. In a furnace for raising steam or other

heating purposes, the combination, substantially as set forth, of a layer of fire-bars, a stationary bearer supporting one end of said fire-bars, and a raising and lowering shaft connected by bracket-arms to a roller which supports the other end of the fire-bars. 15

JEAN PIERRE COTIART.
